(57) **CLAIM**

The ornamental design for a terminal connector substantially, as shown and described.

DESCRIPTION

FIG. 1 is a front view of a terminal connector showing my new design;

FIG. 2 is a rear view thereof;

FIG. 3 is a top view thereof;

FIG. 4 is a bottom view thereof.

FIG. 5 is a side view thereof;

FIG. 6 is another side view thereof; and,

FIG. 7 is a front perspective view thereof.

The broken line showing of the environment is for illustrative purposes only and forms no part of the claimed design.
